UNITED STATES PATENT OFFICE

133,980

DESIGN FOR A PICTURE FRAME

Irving Steinhardt, New York, N. Y.

Application July 10, 1942, Serial No. 107,483

Term of patent 3½ years

To all whom it may concern:

Be it known that I, Irving Steinhardt, a citizen of the United States of America, residing at New York, New York, have invented a new, original, and ornamental Design for a Picture Frame, of which the following is a specification, reference being had to the accompanying drawing, forming a part thereof.

Fig. 1 is a front elevational view of a picture frame showing my new design.

Fig. 2 is a side view thereof.

I claim:

The ornamental design for a picture frame, as shown.

IRVING STEINHARDT.
